DESIGN FOR A HEARING AID

Harold E. Haines, Binghamton, N. Y.

Application May 3, 1946, Serial No. 129,245

Term of patent 14 years

(Cl. D26—14)

To all whom it may concern:

Be it known that I, Harold E. Haines, a citizen of the United States, residing in Binghamton, in the county of Broome and State of New York, have invented a new, original, and ornamental Design for a Hearing Aid, of which the following is a specification, reference being had to the accompanying drawing, forming a part thereof.

Fig. 1 is a top plan view of a hearing aid, showing my new design.

Fig. 2 is a front elevational view thereof.

I claim:

The ornamental design for a hearing aid, as shown.

HAROLD E. HAINES.
